A hand-drawn diagram showing a cross-section of a curved, layered structure, possibly a geological formation or a biological tissue. The structure is depicted with a series of concentric, wavy layers. Four specific points are labeled with numbers: '52' is located on the left side of the top layer; '50' is on the right side of the top layer; '56' is on the right side of the middle layer; and '54' is at the very bottom center of the structure.

CHAIN-DRIVEN RATCHET WRENCH

Benny F. Tackett, Wales, Ky.

Application May 19, 1953, Serial No. 356,051

3 Claims. (Cl. 81—57)

1

This invention relates to hand wrenches. More particularly, the invention has reference to a wrench wherein a chain is in mesh with a pair of rotatably mounted sprockets, one of which has a tool member rotating therewith, means being provided to drive the chain under the control of a user for the purpose of imparting rotary motion to said tool member.

The main object of the present invention is to provide a generally improved chain driven wrench, which will be particularly adapted for use in relatively inaccessible locations, and which will further be adapted to place considerable force upon the tool member during rotation of the same, with a minimum exertion on the part of the user.

A further object of importance is to provide a wrench as stated wherein the chain will be driven by swinging movement of a handle pivotally mounted upon the chain housing, said handle having a ratchet means associated therewith which is particularly formed to engage links of the chain for the purpose of driving the same.

Yet another object is to provide a device of the character referred to wherein the ratchet means will be reversible, so as to permit the chain to be driven in a left or right hand direction as desired, on swinging of the handle.

Another object is to provide a device of the type stated wherein the work-engaging tool member will be detachably connected to the sprocket with which it is rotatable, thus to permit ready substitution of tool members differing from one another as to shape or size.

Another object of importance is to provide a wrench as stated the overall shape of which will be such as to particularly facilitate the use of the wrench in confined areas, the wrench being elongated and of minimum cross sectional area to give effect to this object.

Yet another object is to provide a wrench as described which, in one form thereof, will be of curved formation, thus to make the wrench even more versatile so far as use in relatively inaccessible areas is concerned, the design of the wrench being such as to permit the chain housing to have any of a substantial number of different shapes.

Other objects will appear from the following description, the claims appended thereto, and from the annexed drawings, in which like reference characters designate like parts throughout the several views, and wherein:

Figure 1 is an elevational view of a wrench formed in accordance with the present invention;

2

Figure 2 is an elevational view taken from the right of Figure 1;

Figure 3 is an enlarged fragmentary sectional view taken substantially on line 3—3 of Figure 2;

Figure 4 is an enlarged, fragmentary sectional view taken substantially on line 4—4 of Figure 3;

Figure 5 is an enlarged, fragmentary elevational view of the head portion of the device;

Figure 6 is an enlarged, fragmentary longitudinal sectional view taken substantially on line 6—6 of Figure 1;

Figure 7 is a longitudinal sectional view on line 7—7 of Figure 5;

Figure 8 is a transverse sectional view through the head portion taken substantially on line 8—8 of Figure 5;

Figure 9 is a plan view of a bushing and its associated tool member, per se;

Figure 10 is a plan view of another bushing used in the head portion of the device;

Figure 11 is an elevational view of a work-engaging tool member, per se;

Figure 12 is a reduced elevational view of a modified form of wrench; and

Figure 13 is an enlarged, fragmentary, longitudinal sectional view through the housing of the form of wrench illustrated in Figure 12.

In the form of the invention shown in Figures 1—11, the wrench includes an elongated, straight, tubular housing 10 formed open at its opposite ends. The housing can be appropriately considered as having a handle end and a head end, and the formation of the housing at each of said ends will be described in turn.

At its handle end, the housing 10 is formed with transversely aligned, flat, longitudinal extensions 12, said extensions being formed with transversely aligned openings receiving the opposite ends of a pivot pin 14. Pivot pin 14, as shown in Figure 3, may be a conventional bolt, to which a nut is applied for the purpose of holding the pin assembled with its associated extensions 12.

Rotatably mounted on the pin 14, between the extensions 12, is a chain sprocket 16, and meshing with said sprocket is a chain 18.

A handle has been designated by the reference numeral 20, and at its inner end, has fork arms apertured for extension of pin 14 therethrough, said fork arms embracing the sprocket 16 between them as best shown in Figure 3. In this way, the handle 20 is pivotally mounted upon its associated housing 10.

The handle is provided, at said inner end thereof, with a V-shaped pawl 22, having teeth 24 at its opposite ends engageable in selected links of

the chain 18. The pawl is fulcrumed medially between its ends upon a pin 26 extending between the fork arms of the handle, a spring-loaded ball detent 28 being provided in the handle and being adapted to releasably hold the pawl against retrograde movement from selected positions to which it is pivotally adjusted about the axis of pin 26. As will be noted, the pawl is provided, medially between its ends, with angularly related surfaces either of which is engageable by the ball element, said surfaces intersecting at a point 30.

By reason of the construction illustrated, swinging of the handle in one direction will drive the chain 18, swinging of the handle to its return position, in an opposite direction, permitting the pawl to ratchet over the lengths of the chain. When, subsequently, the handle is again swung in the first-named direction, the chain will again be driven. A ratchet means is thus provided by the pawl 22, cooperating with the chain, the chain constituting the ratchet and the pawl being of the reversible type to permit the chain to be driven in either direction, as desired.

At that end thereof remote from the handle 20, the housing 10 is provided with a head 32 (Figures 6 and 7). Head 32 has an inner end portion extending into the adjacent open end of the housing 10, said inner end portion of the head being tapered to provide guide surfaces for the opposite flights of the chain. The tapered inner end portion of the head 32 merges into an outer end portion, which is bifurcated to define form arms 34.

The head 32 is brazed or otherwise fixedly secured to the adjacent end of housing 10, and to hold the fork arms 34 against spreading, a connecting screw 36 can be extended therebetween (Figure 7).

In the outer ends of the fork arms, transversely aligned, circular openings of substantial size are formed, and rotatably mounted in one of said openings is a bushing 43, the other opening having a bushing 38 rotatably mounted therein.

Between the bushings 38, 43, a sprocket 42 is disposed, said sprocket being in mesh with the chain 18. Sprocket 32 has a central, non-circular aperture, said aperture being approximately square in the illustrated example of the invention. A tool member 44 is engaged in said aperture, the tool member having, at one end thereof, a work-engaging formation which projects laterally of the head 32. It will be understood that the work-engaging formation can be of any desired type, whether male or female, and also can be of any selected size. The tool member 44, intermediate its ends, is provided with circumferentially spaced shoulders 45 that engage against the outer end of the bushing 38.

In one end, the tool member 44 has a threaded socket, receiving a clamp screw 46. The head of screw 46 is of tapered formation, and overlies the bushing 43, and it will thus be seen that on threading of the screw 46 inwardly of its associated recess, the tool member will be securely connected to the sprocket 42, and will be rotated with the sprocket whenever the chain is driven. The tool member can of course be readily removed, for substitution of another tool member differing in shape or size.

In the work-engaging portion of the tool member, it may be desirable to provide a ball lock 48, but of course, said lock can be omitted in a commercial embodiment.

In Figures 12 and 13 there is shown a modified form wherein the housing has been designated by the reference numeral 50, and though elongated and relatively narrow like the housing 10, the housing 50 is curved throughout its length. The purpose of this construction is to permit the housing 50 to be extended into relatively inaccessible locations in which the straight housing 10 cannot be used. Conversely, the housing 10 might be usable in certain locations in which the housing 50 is incapable of use.

Apart from the arcuate shape thereof, the device shown in Figures 12 and 13 is similar to that shown in the first form of the invention. The arcuate shape of the housing, of course, makes it advisable that pins 54 be extended between the flights of the chain 52 of the structure, at locations spaced longitudinally of the housing 50. Spacer sleeves 56 are circumscribed about the pins, to hold the flights of the chain apart throughout the length of the housing.

The head formation of the modified form is the same as that in the first form of the invention, and similarly, the handle and ratchet means will be identical to that previously described herein.

In use, the tool member 44 is applied to the work to be rotated, after which the handle 20 is grasped and swung back and forth with the ratchet means defined by pawl 22 in a selected position of pivotal adjustment. This will cause the chain to be driven in one direction, the pawl driving the chain when the handle is swung in said direction and ratcheting over the chain links when the handle is swung in a reverse direction.

Great force is applied to the work, for the purpose of rotating the same, since the handle affords considerable leverage, which is translated into rotary movement by the sprocket and chain means illustrated. At the same time, the tool 40 has the desirable characteristics of relative lightness and compactness, permitting its use in confined quarters.

It is believed apparent that the invention is not necessarily limited to the specific use or uses 45 thereof described above, since it may be utilized for any purpose to which it may be suited. Nor is the invention to be necessarily confined to the specific construction illustrated and described, since such construction is only intended to be 50 illustrative of the principles of operation and the means presently devised to carry out said principles, it being considered that the invention comprehends any minor change in construction 55 that may be permitted within the scope of the appended claims.

What is claimed:

1. A chain driven ratchet wrench comprising an elongated tubular housing having a head end and a handle end, said handle end being formed with a pair of transversely flat extensions, said pair of extensions each having a transversely disposed opening, a pivot pin secured in said openings, a first chain sprocket rotatably secured on said pin between said pair of extensions and spaced therefrom, a handle having its inner end formed with a pair of arms disposed in face to face relation, said pair of arms having an aligned aperture therethrough and being disposed one on each side of said sprocket between said pair of extensions and having said pivot pin traversing their associated apertures for pivotal movement of said handle relative to said housing; a pawl pivotally secured to said handle at its inner end between said pair of forked arms, a pair of bifurcated arms on said housing at the head end

remote from said handle, an end portion secured to said head end between said pair of bifurcated arms, said end portion being tapered inwardly from its end on each of its sides between and transversely disposed relative to said bifurcated arms, a transversely aligned opening in each of said pair of bifurcated arms, a bushing in each opening, an out-of-round work member rotatably positioned in said bushings and projecting at one end from one of said bushings to form a work-engaging member, said work member having a shoulder engageable with said one of said bushings for restraint of movement in one direction of said work member through said bushing, a screw releasably threaded in said work member at its non-projecting end and axially thereof, said screw having its periphery overlying the other one of said bushings and operable to restrain movement of said work member through said bushings in the other direction, a second chain sprocket disposed between said bushings and having an aperture adapted to receive said work member therethrough for rotational movement therewith, and a chain operatively connecting said first and second sprockets and having successive links drivably engaged by said pawl for movement in a selected direction upon rotation of said handle relative to said housing.

2. A chain drive ratchet wrench comprising an elongated straight tubular housing having a head end and a handle end, said handle end being formed with a pair of flat extensions disposed in spaced face to face relation, said pair of extensions each having a transversely disposed opening in each, a pivot pin secured in said openings, a first chain sprocket rotatably secured on said pin between said pair of extensions and spaced therefrom, a handle having its inner end formed with a pair of arms disposed in face to face relation, said pair of arms having an aligned aperture therethrough and being disposed one on each side of said sprocket between said pair of extensions and having said pivot pin traversing their associated apertures for pivotal movement of said handle relative to said housing, a pawl pivotally secured to said handle at its inner end between said pair of arms, a pair of bifurcated arms on said housing at the head end remote from said handle, an end portion secured to said head end between said pair of bifurcated arms and being tapered inwardly from its end on each of its sides transversely disposed relative to said pair of bifurcated arms, a bushing in each opening, an out-of-round work member rotatably positioned in said bushings and projecting at one end from one of said bushings to form a work-engaging member, said work member having a shoulder engageable with said one of said bushings for restraint of movement in one direction of said work member through said bushing, a screw removably threaded in said work member at its non-projecting end axially thereof, said screw having its periphery overlying the other one of said bushings and operable to restrain movement in the other direction of said work member through said bushings, a second chain sprocket disposed between said bushings and having an aperture adapted to receive said work member therethrough for rotational movement therewith, and a chain operatively

5 connecting said first and second sprockets and having successive links drivably engaged by said pawl for movement in a selected direction upon rotation of said handle relative to said housing.

10 3. A chain drive ratchet wrench comprising an arcuately shaped elongated tubular housing having a head end and a handle end, said handle end being formed with a pair of flat extensions disposed in spaced face to face relation, said pair of extensions each having a transversely disposed opening in each, a pivot pin secured in said openings, a first chain sprocket rotatably secured on said pin between said pair of extensions and spaced therefrom, a handle having its inner end formed with a pair of arms disposed in face to face relation, said pair of arms having an aligned aperture therethrough and being disposed one on each side of said sprocket between said pair of extensions and having said pivot pin traversing their associated apertures for pivotal movement of said handle relative to said housing, a pawl pivotally secured to said handle at its inner end between said pair of arms, a pair of bifurcated arms on said housing at the head end remote from said handle, an end portion secured to said head end between said pair of bifurcated arms and being tapered inwardly from its end on each of its sides transversely disposed relative to said pair of bifurcated arms, a transversely aligned opening in each of said pair of bifurcated arms, a bushing in each opening, an out-of-round work member rotatably positioned in said bushings and projecting at one end from one of said bushings to form a work-engaging member, said work member having a shoulder engageable with said one of said bushings for restraint of movement in one direction of said work member at its non-projecting end axially thereof, said screw having its periphery overlying the other one of said bushings and operable to restrain movement in the other direction of said work member through said bushings, a second chain sprocket disposed between said bushings and having an aperture adapted to receive said work member therethrough for rotational movement therewith, a chain operatively connecting said first and second sprockets and having successive links drivably engaged by said pawl for movement in a selected direction upon rotation of said handle relative to said housing, and a plurality of spacer sleeves rotatably secured in said housing in spaced relation and operable to separate the flights of said chain.
